APPARATUS FOR THE COUNTERCURRENT LIQUID TREATMENT OF YARN

Thomas L. Nash, South Parkersburg, W. Va., assignor to American Viscose Corporation, Philadelphia, Pa., a corporation of Delaware

Application January 15, 1952, Serial No. 266,495

4 Claims. (Cl. 68—176)

This invention relates to a liquid treating process for continuously moving filamentary material of either natural or artificial origin. More particularly this invention relates to a continuous countercurrent liquid treating process wherein the circulatory effects of the filamentary material in the bath are reduced to a minimum.

Continuous processing of filaments and tows is accomplished by passing the same successively through various chemical and other liquid treating baths. Depending upon the effectiveness of the bathing process, the filamentary materials must remain submerged in each of the baths a certain minimum period of time. Attempts to satisfy increased production demands at the expense of these minimum bathing time periods have caused improper processing results. To offset these improper results and yet to simultaneously speed up production, the so-called countercurrent liquid treating process has been developed. By this process the flow of the liquid in open liquid treating baths is oppositely directed to the movement of the filament or tow therethrough. In this way the yarn is exposed to a greater quantity of treating liquid in a given period of time and greater quantities of yarn can be satisfactorily handled.

It has been found, however, that due to the drag effect of the filament or tow, the bath immediately adjacent thereto circulates in the direction of the filament or tow movement. By reducing this drag effect it was realized that the yarn could be exposed to still greater quantities of treating liquid in a given time period and that furthermore the greater hydrodynamic forces due to a real and substantial countercurrent immediately adjacent the area of filament or tow travel would simultaneously increase the penetration of the surface film of the filaments and thereby speed up the chemical actions which take place in the filaments.

It is a principal object of this invention to eliminate this objectionable circulatory flow of the bath adjacent the filament or tow and to effectuate countercurrent hydrodynamic forces of treating liquids by providing a series of baffles in the bath through which the filament and bath are required to move in opposite directions and to thereby further increase production by use of existing countercurrent treating equipment.

Other objects will appear in the course of the following description. My invention is illustrated in the accompanying drawing wherein:

Figure 1 is a side elevational view in section of an embodiment of the invention wherein the yarn passes through a plurality of liquid treating baths which are designed in accordance with a first embodiment of this invention;

Figure 2 is a plan view of a portion of the embodiment shown in Figure 1;

Figure 3 is a section on the line III—III of Figure 2;

Figure 4 is an enlarged view of the section on line IV—IV of Figure 3;

Figure 5 is another embodiment showing a modified sectional configuration of a pair of baffles;

2

Figures 6 through 8 are still further embodiments showing different types of baffles that may be used in practicing this invention.

Referring first to Figure 1 of the drawing, a series of open bath troughs or vessels 3, 4, and 5 are shown placed end to end. Each of these vessels is interconnected between a liquid supply means and a liquid discharge means such that the liquid treating solution passes successively from one bath to another. Thus a fresh liquid treating solution is supplied to vessel 5 by means of an inlet pipe 6 at one end of the vessel 5 the length of which is longitudinally coincident with a path for transferring a running continuous filamentary material therethrough. The treating solution thereupon passes through the vessel from left to right in the lengthwise direction of the vessel to discharge pipe 7 at the opposite end of the vessel. Pipe 8 interconnects discharge pipe 7 with inlet pipe 9 of bath 4. By a similar arrangement, the liquid treating solution is then passed through bath 4 to a discharge pipe 10 from the left end to the right end of the bath. Likewise, the liquid treating solution passes from left to right through bath 3 by way of its inlet pipe 11 and its waste discharge pipe 12. Frusto-conical deflector plates 17 surround each of the inlet pipes 6, 9, and 11 and reduce turbulence in each of the baths. Thus it is to be noted that the liquid treating solution passes through each of the vessels from left to right without undue turbulence. It is to be noted that the discharge pipes 7, 10, and 12 extend upwardly through the bottom and terminate sufficiently above the bottom of the trough to assure a minimum liquid level in the bath which is above the lower extremity, edge, or surface of the downwardly extending baffles 16 which will be more fully described hereinafter.

The hydrodynamic pressure which is employed to circulate the liquid treating solution between the successive troughs may be developed by means of the pumps 13 and 14 shown on the drawing or by any other convenient means such as by air jets or steam jets.

Each of the vessels is provided with one or more upwardly extending baffles 15 which extend across the full width of the vessel and are affixed to the bottom thereof. Vertically aligned with each of the upwardly extending baffles is a corresponding number of downwardly extending baffles 16 which also extend across the full width of the vessel. Downwardly extending baffles 16 are removably mounted in notches 40 on the upper surface of the vessel and are retained therein by means of removable plates 41. This removable feature of the downwardly extending baffles provides greater ease in lacing the filamentary material between the vertically aligned baffles as will be hereinafter described more fully.

While the drawing illustrates this system as embodying three successive baths, it is to be understood that any greater or lesser number of baths could be employed within the scope of the invention. Likewise, although the filament or tow is disclosed as being treated with but a single liquid treating solution, it is to be understood that the filament or tow may be passed in succession through a plurality of different liquid treating solutions without departing from the spirit of the invention.

As shown in Figures 1 and 2 of the drawing a pair of drums 19 and 20 are journaled on the upper edge of each of the vessels, one adjacent each end thereof. As shown in Figures 1, 2, 4 and 5, the filamentary material passes through a plane that is midway between the opposed edges or surfaces of the upper and lower baffles as a result of the positioning of the drums 19 and 20 above and in approximately tangential relationship to such plane. The shaft of drum 19 of each pair extends beyond the edge of its respective vessel and is driven by means of a mechanical connection through gears 33 and 34 and shaft 35 to a rotating source not shown on the

drawing. Drums 20 are shown as idler rollers but it is to be understood that each of the drums 19 and 20 could be driven. Each pair of drums 19 and 20 are preferably slightly skewed relative to one another to cause the filamentary material to helically advance therealong.

Tracing the manner in which the filamentary material passes from a source such as a spinneret and coagulating bath or a wound package thereof through the liquid treating vessel to a collecting means or subsequent processing station, the filamentary material 18 passes from the source through the squeeze rollers 21 and 22, helically around the drums 19 and 20 through the bath 3, between baffles 15 and 16 from right to left, and between the squeeze rollers 23 and 24. Likewise, the filamentary material passes helically around the drums 19 and 20 of baths 4 and 5 between associated baffles 15 and 16 from right to left between respective squeeze rollers 25 and 26, and 27 and 28 and on to the collecting means or subsequent processing station.

Referring to Figures 2 and 3 of the drawing, it is to be noted that the vertically aligned baffles are positioned across the vessels preferably substantially perpendicular to the path of filament movement and spaced apart such that a satisfactory amount of bath liquid treating solution will flow therethrough. It should be noted that the constricted rectangular opening 29 between the baffles provides the only means for the opposite movement of the filament and the bath solution and that in this way a truly effective countercurrent spinning process is assured.

It should also be noted that the opposed extremities of each pair of vertically aligned baffles are rounded in cross-section. This feature of the present invention prevents undesirable circulatory currents in the flow of the bath solution adjacent the constricted openings between the baffles.

In Figure 5 of the drawing, a second embodiment of the invention is disclosed wherein the opposed extremities of the vertically aligned baffles are rounded in a more gradual manner. The gentle slope of the baffles in this embodiment permits high liquid flow speeds through the successive baths without increased turbulence therein.

In Figure 6 of the drawing still another embodiment of the invention is disclosed. In this embodiment of the invention as in the previously disclosed embodiment, the contour of the upper surface or edge of the upwardly extending baffle 30 is a straight line. However, the lower surface or edge of the adjacent downwardly extending baffle includes grooves 32 through which pass the respective turns of the helices on the filament advancing drums 19 and 20. This feature of this embodiment of the invention increases the flow velocity of the treating liquid adjacent the filamentary material and thereby creates greater hydrodynamic forces which more effectively penetrate its film surfaces.

Figure 7 and Figure 8 disclose structural modifications of the embodiment of the invention disclosed in Figure 6. In Figure 7 the lower surface of the downwardly extending baffle includes notches or grooves 32'. In Figure 8 both the upper surface of the upwardly extending baffle and the lower surface of the downwardly extending baffle are similarly notched or grooved as at 32" to accommodate the various helices on the filament advancing drums.

The apparatus of the above-described invention may be employed by processing the filamentary material in various ways such as for washing, desulphurizing, bleaching, sizing, lubricating, and other conditioning processes of filamentary materials. Thus the liquid treating solutions which are selected to be used in the various baths are dependent upon the manner in which the yarn is to be ultimately processed. It is to be also emphasized that the above liquid treating apparatus may be used to condition or treat any type of yarn, filament, tow, narrow band, ribbon, or other filamentary material of either natural or artificial origin.

While preferred embodiments of the invention have

been disclosed, the disclosure is intended to be illustrative only and it is to be understood that changes and variations may be made without departing from the spirit and scope of the invention as defined by the appended claims.

5 I claim:

1. Apparatus for the liquid-treatment of filamentary material comprising a vessel for containing a liquid and having its length longitudinally coincident with a path for said material extending through the vessel, means 10 at one end only of the vessel for introducing liquid into it, overflow means at the other end of the vessel for maintaining the liquid therein at a predetermined level, a fixed baffle intermediate the ends of the vessel extending upwardly from the bottom of the vessel and extending 15 across the entire width of the vessel, a removably mounted baffle extending from a position above the liquid level downwardly to a position below the liquid level and extending across the entire width of the vessel in generally vertical alignment with the first-mentioned baffle and 20 with its lower surface adjacent the upper surface of the first-mentioned baffle to provide at least one constricted opening between the baffles, the aggregate of each such opening providing the entire passageway for flow of the liquid and movement of a filamentary material there- 25 between, the opposed surfaces of each of the baffles having a gradual curvature as viewed from the end of the baffle to minimize turbulence in the liquid, and a pair of rollers one thereof being mounted between the baffle and each end of the vessel, the lower portions of the rollers 30 extending below the predetermined level of the liquid into approximately tangential relationship with a plane midway between the opposed surfaces of the baffles.

2. Apparatus for the liquid-treatment of filamentary material comprising an open vessel for containing a liquid 35 and having its length longitudinally coincident with a path for said material extending through the vessel, means at one end only of the vessel for introducing liquid into it, overflow means at the other end of the vessel for maintaining the liquid therein at a predetermined level, 40 a fixed baffle intermediate the ends of the vessel extending upwardly from the bottom of the vessel and extending across the entire width of the vessel, a removably mounted baffle extending from a position above the liquid level downwardly to a position below the liquid level and extending across the entire width of the vessel in generally vertical alignment with the first-mentioned baffle and with its lower surface adjacent the upper surface of the first-mentioned baffle to provide at least one constricted opening between the baffles, the aggregate of each such opening providing the entire passageway for flow of the liquid and movement of a filamentary material there- 45 between, the opposed surfaces of each of the baffles having a gradual curvature as viewed from the end of the baffle to minimize turbulence in the liquid, and a pair of rollers, one thereof being mounted between the baffle and each end of the vessel, the lower portions of the rollers 50 extending below the predetermined level of the liquid into approximately tangential relationship with a plane midway between the opposed surfaces of the baffles, and the upper portions of the rollers extending to a level 55 above the upper baffle and the top of the vessel.

3. Apparatus for the liquid-treatment of filamentary material comprising an open vessel for containing a liquid and having its length longitudinally coincident with a path for said material extending through the vessel, means 60 at one end only of the vessel for introducing liquid into it, overflow means at the other end of the vessel for maintaining the liquid therein at a predetermined level, a fixed baffle intermediate the ends of the vessel extending upwardly from the bottom of the vessel and extending 65 across the entire width of the vessel, the contour of the upper edge of the upwardly extending baffle being linear as viewed from the side of the baffle, a removably mounted baffle extending from a position above the liquid level downwardly to a position below the liquid level and ex- 70 tending across the entire width of the vessel in generally 75 tending across the entire width of the vessel in generally

vertical alignment with the first-mentioned baffle, the lower edge of the downwardly extending baffle abutting the upper edge of the upwardly extending baffle, the lower edge of the downwardly extending baffle comprising at least one groove which provides a constricted opening between the abutting baffles, the aggregate of each such opening providing the entire passageway for flow of the liquid and movement of a filamentary material therebetween, the opposed edges of the baffles having, at each groove, a gradual curvature as viewed from the end of the baffles to minimize turbulence in the liquid, and a pair of rollers one thereof being mounted between the baffle and each end of the vessel, the lower portions of the rollers extending below the predetermined level of the liquid into approximately tangential relationship with a plane midway between the opposed edges of the baffles at each groove.

4. Apparatus for the liquid-treatment of filamentary material comprising an open vessel for containing a liquid and having its length longitudinally coincident with a path for said material extending through the vessel, means at one end only of the vessel for introducing liquid into it, overflow means at the other end of the vessel for maintaining the liquid therein at a predetermined level in the vessel, a fixed baffle intermediate the ends of the vessel extending upwardly from the bottom of the vessel and extending across the entire width of the vessel, the upper edge of the upwardly extending baffle including a groove, a removably mounted baffle extending from a position above the liquid level downwardly to a position below the liquid level and extending across the entire width of the vessel in generally vertical alignment with

5
